(57) CLAIM

I claim the ornamental design for a barbecue grill plate, as shown and described.

DESCRIPTION

FIG. 1 is a perspective view of barbecue grill plate in accordance with the preferred embodiment of the present invention, showing my design;

FIG. 2 is a front view of the barbecue grill plate shown in FIG. 1;

FIG. 3 is a rear view of the barbecue grill plate shown in FIG. 1;

FIG. 4 is a left side view of the barbecue grill plate shown in FIG. 1;

FIG. 5 is a right side view of the barbecue grill plate shown in FIG. 1;

FIG. 6 is a top view of the barbecue grill plate shown in FIG. 1;

FIG. 7 is a bottom view of the barbecue grill plate shown in FIG. 1; and,

FIG. 8 is a perspective view of the barbecue grill plate, with broken lines showing a grid for a barbecue grill that is unclaimed in and forms no part of the claimed design.
